(57) **CLAIM**

The ornamental design for fastener assembly, as shown and described.

DESCRIPTION

FIG. 1 is a perspective representational view of the fastener assembly illustrating a front tilted side view of the product; FIG. 2 is a perspective representational view of the fastener assembly illustrating a front top side view of the product; FIG. 3 is a side view of the fastener assembly illustrating one side of the product; FIG. 4 is another side view of the fastener assembly illustrating another side of the product; FIG. 5 is an overhead view of the product; FIG. 6 is another overhead view of the product (opposite of FIG. 5); FIG. 7 is a tilted side perspective view of the fastener assembly with all pieces of the fastener snapped together; FIG. 8 is another side perspective view of the fastener assembly with all pieces of the fastener snapped together; FIG. 9 is a side view of the fastener with all pieces of the fastener assembly snapped together; FIG. 10 is another side view of the fastener with all pieces of the fastener assembly snapped together (opposite of FIG. 9); FIG. 11 is an overhead view of the fastener assembly with all pieces of the fastener snapped together; and, FIG. 12 is another overhead view of the fastener assembly with all pieces of the fastener snapped together (opposite of FIG. 11).

It should be understood that the labels used herein for describing orientation (e.g. front, back, side, top, and bottom) are merely for reference, and the design may be disposed in any manner and still be within the scope of the present invention. The shading lines are for illustrative purposes only and forms no part of the claimed design.

The broken line showing is for illustrative purposes only and forms no part of the claimed design.

The drawings of particular orientations of the present invention are for illustrative purposes and are not limitations on the present invention.

1 Claim, 3 Drawing Sheets
